UNITED STATES PATENT OFFICE.

MAUD C. FOX, OF NEW YORK, N. Y.

DEVICE FOR ILLUMINATING CLOCKS OR THE LIKE.

Application filed August 24, 1925. Serial No. 52,241.

This invention relates to an illuminating device, and the primary object of the same is to provide a device of this class having novel illuminating elements and structural features whereby a clock or other article is supported and wherein such article may be mounted for movement toward or away from a central orifice so as to be visible either during day time or night time.

A further object of the invention is to generally construct a device of the class specified with advantageous features for convenience in manipulating the same and including comparatively simple means for shifting the clock or other article to be displayed forwardly and rearwardly without in the least affecting its operation or requiring a skilled knowledge of mechanical actuation to properly move the clock or other article relatively to the transparent enclosure therefor to effect the position of such article as may be desired.

With these and other objects and advantages in view, the invention consists in the construction and arrangement of the several parts which will be more fully herein-after described and claimed.

In the drawings:

Fig. 1 is a front elevation of a clock embodying the features of the invention.

Fig. 2 is a side elevation with parts broken away.

Fig. 3 is a section on the line 3—3, Fig. 2.

Fig. 4 is a horizontal section on the line 4—4, Fig. 1, and showing the frame for the lamp sockets broken away.

Fig. 5 is a diagrammatic view showing automatically operating electrical means for igniting and extinguishing the electric lights.

The numeral 5 designates a back or supporting frame or member having a back plate 6 applied thereto and of dished form or provided with a forwardly projecting rim flange 7. The back frame 5 and plate 6 are preferably circular in contour and the diameter of the plate 6 is greater than that of the frame 5, to provide a space 8 between the flange 7 and the perimeter of the back frame 5 for a purpose which will be presently explained. Projecting forwardly from the frame or member 5 is a guide or socket 9, which may be of any preferred form but as shown is preferably polygonal in contour and may be either of metal, wood or

other material suitable for the purpose and which serves to support an article to be displayed, in the present instance a clock. The guide or socket 9 has an opening 10 extending fully through the same and coinciding with an opening of similar diameter through the frame or member 5 and back plate 6 as at 11 and 12. This opening 10, which is continued rearwardly through the back plate 6, as just explained, is preferably of circular contour and an enclosure 13 here shown as a block casing, is fitted to have sliding movement therein. From the back frame 6 ribs 14 extend forwardly to a central rim or annulus 15, the said ribs 14 being intersected by a bracing annulus or circular bar 16 concentric with relation to the rim 15. The ribs 14 at a comparatively short distance from the back frame or member 5 bulge outwardly and then curve inwardly from a point at about which they intersect the bracing annulus 16 and then turn inwardly in arcs to the rim 15. Within these ribs and bracing annulus is a lining 17, of mica or similar material, which is similarly bulged in a forward direction as shown by Figs. 2 and 4 and indicated by shading in Fig. 1, the rear edge of this lining being held in the spaces 8 between the rim flange 7 of the back plate 6 and the perimeter of the back frame or member 5. Instead of using mica for the lining 17 other suitable translucent material may be adopted at will. The lining 17 is shielded and protected as well as maintained in its bulged form by the ribs 14 and bracing annulus 16 without interfering with its translucent character. Secured to the back frame or member 5 and extending through the back plate 6 are incandescent electric light sockets 18, two being shown in the present instance and to which electric circuit wires 19 are secured as usual and supplied by a lead wire 20 from a suitable source of electrical current supply or generation. Within the sockets 18 incandescent electric lamps 21 are removably fitted as usual and project forwardly in horizontal planes on opposite sides of the socket or guide frame 9, the said electric lights projecting forwardly beyond the rim 15. It will be seen that the ribs 14 with the translucent lining 17 have a central dip or surround a central outwardly diverging open space 22 as clearly shown by Fig. 4, and as a consequence light will be transmitted

through the surrounding transparent wall provided by the lining 17.

Where the article to be displayed is a clock the casing 13 will contain clock works 5 of any suitable type and the latter are enclosed or fully protected by the casing, and the back will have an exposed winding and setting means as indicated generally at 23, and at the front of the casing is the usual 10 form of clock dial 24 with a glass or other transparent enclosure 25. The lower portion of the casing 13 at the center is provided with a horizontal rack 26, which is engaged by a pinion 27 mounted on a laterally projecting arbor or stem 28 having an exteriorly located, milled head or other suitable operating device 29, and whereby the casing 13 may be moved rearwardly or forwardly by operating the arbor or stem 28 15 in reverse directions. When the casing 13 contains a clock the arbor or stem 28 of the clock is held in suitable bearings and may be very easily operated to obtain the adjustment desired. The casing 13 is of a diameter 20 to permit the same to be moved into the rim 15 for displaying the face of the clock or other article during daylight, at which time the incandescent electric lamps 21 will be extinguished. At night the casing 13 as a 25 whole will be shifted rearwardly as shown by Fig. 5, and at this time the incandescent lights 21 will be active or glowing and fully illuminate said face. The device is also 30 serviceable as a night lamp but is particularly intended to render a clock easily discernible from a distance to ascertain the time at any hour of the night or while a room or other enclosure is in darkness.

The back plate 6 is hinged at the central 35 lower portion thereof, as at 30, and has a latch plate 31 hinged to the upper portion thereof as at 32, the said latch plate being formed with a slot 33 therethrough to engage over a staple or analogous device 34 carried by an upwardly projecting portion 35 at the center of the back frame or member 5. The latch plate 31 also carries a pivoted hook 36, which is adapted to be 40 pushed through the staple 34 when the latter has been inserted through the opening or slot 33, as clearly shown by Fig. 3. The hook 36 is brought into engaging position with relation to the staple 34 by moving the 45 latch plate 31 upwardly into normal position and effecting a rearward projection of the end of the staple 34 through the opening 33. When it is desired to open the back plate 6, the hook 36 is withdrawn from the staple 50 and the plate 31 carrying the said hook 36 is turned downwardly or released from the staple 34 and then the back plate 6 may be 55 opened. The said back plate may be easily reset in normal position and locked through 60 the medium of the latch plate 31 and hook 36.

with relation to the staple 34, as hereinbefore explained. The lower portion of the socket 9 for the casing 13 is suitably slotted, as at 37, for convenience in application and operation of the rack 26 and pinion 27. 70

It is also proposed to ornament the enclosure as a whole by suitable design or pleasing configuration members as at 38 and 75 39, but it will be understood that the invention in the present instance is not limited by these ornamental accessories.

In some instances the lining 17 may be suitably colored and the ribs 14 and bracing annulus 16 and ornamentation features above noted correspondingly colored, to render the improved lamp clock pleasing in 80 appearance.

In Fig. 5 a variation of the previous structure is disclosed and consists in providing means for opening or closing the electric circuit to the electric lights 21 in accordance with the movement or adjustment of the casing 13. This mechanism consists of insulated projections 40 secured or applied to the casing 13 for operating an electric switch lever 41 with relation to a contact 42, electrically connected by a wire 43 with one of the circuit wires 44 of the electric lamps 21. The switch lever 41 is connected by a wire 45 with one side of the 90 source of electric current 46, which may be of any character sufficient to illuminate the incandescent lamps 21. The other side 47 of the source of electric current leads directly to the lamps. As the casing 13 containing the clock mechanism is shifted rearwardly, the lever 41 is moved into engagement with the contact 42 thereby closing the electric circuit to the lamps 21 which will 95 remain illuminated as long as the casing 13 and parts carried thereby are in their rearward position. When the casing 13 and parts carried thereby are moved forwardly to bring the dial against the opening of the frame, the lever 41 is disengaged from the contact 42 and the lamps 21 are instantly 100 extinguished. The structure shown by Fig. 5 is diagrammatically illustrated and it will be understood that any form of means for operating the switch lever 41 as well as any form of switch for opening and closing the electric circuit to the lamps 21 may be used. It will also be understood that any means may be employed for shifting or adjusting the casing 13 and parts carried thereby and that the apparatus may be used with or without the means for opening or closing the electric circuits to the lamps through the actuation or shifting movement of the clock 105 casing 13 and parts carried thereby. 110

What is claimed as new is:

1. The combination of a skeleton-like frame having an approximately centrally arranged opening in its forward end, a lining of translucent material in said frame, 115 120 125 130

said lining having an aperture registering with the central opening in said frame, lighting devices mounted in said frame laterally of said central opening, and an article supported in said frame at a distance from said opening and illuminated by said lighting devices.

2. The combination of an enclosure having in its forward end an approximately centrally arranged opening and a plurality of apertures disposed around said opening, said enclosure also having a plurality of apertures in its side walls, translucent means covering said apertures, lighting means mounted in said enclosure laterally of said central opening, and an article supported behind said central opening and illuminated by said lighting devices, said article being movable toward and away from the central opening in said enclosure.

3. The combination of a frame structure having a translucent lining, the frame structure having a front depressed portion with an opening therein, the remainder of said front portion of the frame structure and lining projecting outwardly beyond the opening and forming an internal recess around said opening, lighting means within said recess, and means for supporting an object within said frame structure rearwardly of said opening and having its forward end illuminated by the light rays from said lighting means.

4. The combination of a frame structure having a front depression with an opening therein, a translucent lining for the frame structure, the frame structure and lining around said depression forming a forward projection and providing a recess within the

frame around said opening, lighting means disposed within said internal recess, and a support within said frame for an article to be displayed, said support having its forward end opposite said opening to the rear of the latter.

5. A device of the class specified, comprising a skeleton-like enclosure having a translucent lining, said enclosure and its lining having a central opening, illuminating means in said enclosure, means for supporting an object behind said central opening and said illuminating means, said supporting means being movable toward and away from said opening, and means operable by the movement of said supporting means for illuminating and extinguishing said illuminating means.

6. In a device of the class specified, the combination of a skeleton-like supporting frame having a translucent lining and also having a forwardly projecting portion and a centrally arranged depression formed with an opening, electric lighting means mounted in the frame, an electric circuit connecting said lighting means to a source of electric current, a casing movable rearwardly and forwardly with relation to said opening, said casing, when moved rearwardly, having its forward end exposed to the light rays of the lighting means and, when moved forwardly, having its forward end closing said opening, and switch means actuated by said casing during its rearward and forward movements for closing and breaking said electric circuit.

In testimony whereof I have hereunto set my hand.

MAUD C. FOX.
